CLAIM

The ornamental design for a carton serialisation machine, as shown and described.

DESCRIPTION

FIG. 1 is a right front perspective view of a carton serialisation machine according to our new design;

FIG. 2 is a left front perspective view thereof;

FIG. 3 is front view thereof;

FIG. 4 is a rear view thereof;

FIG. 5 is a right side view thereof;

FIG. 6 is a left side view thereof;

FIG. 7 is a top view thereof; and,

FIG. 8 is bottom view thereof.

The broken lines illustrate portions of the carton serialisation machine that form no part of the claimed design.
